UNITED STATES PATENT OFFICE

2,203,725

TELEPHONE SYSTEM

Irvin Geitgey, Elyria, Ohio, assignor to Associated Electric Laboratories, Inc., Chicago, Ill., a corporation of Delaware

Application August 16, 1938, Serial No. 225,165

19 Claims. (Cl. 179—27)

This invention relates to telephone systems in general, but is concerned more particularly with toll switching arrangements for handling toll or long distance traffic between two toll exchanges. The object of the invention is the provision of circuit arrangements whereby the toll operator at either toll exchange may extend and complete connections to called lines in the other toll exchange without the assistance of the other toll operator.

The present invention may be considered as an improvement to the circuit arrangements disclosed in the Crocker et al. Patent 1,883,589, issued October 18, 1932, in the method and apparatus for extending and completing toll calls from one toll exchange to a second toll exchange. In the present invention, when a toll call is received by a toll operator in one of the toll exchanges for a subscriber's line located in the second toll exchange, the toll operator directly completes the toll connection over automatic switches in both exchanges to the called line without the aid of the toll operator at the other exchange. The circuits and apparatus also provide the originating toll operators with complete supervision over the extended connection. One of the features relates to improved repeater circuits for extending calls to the distant toll exchange and for translating reverse battery supervision over the inter-exchange trunk line to high resistance supervision. Another feature relates to the improved repeater circuit for controlling automatic ringing and manual re-ring of the called party.

The foregoing features together with others not specifically mentioned will be described in connection with the description of the operation of the invention, reference being had to the accompanying drawings, comprising Figs. 1 to 6, inclusive. The drawings show by means of the usual circuit diagrams when considered in conjunction with the Crocker et al. Patent 1,883,589 and the Wicks Patent 1,315,444, issued September 9, 1919, the essential equipment for a complete toll service switching system.

Fig. 1 corresponds to part of the inward toll operator's position and link circuit shown in Figs. 2 and 3 of Patent 1,883,589, the relays, keys, conductors, and contacts having the same numerical characters as in that patent. Only sufficient circuit details of this patent are shown in the drawings to enable the invention to be fully described and understood, it being understood that the conductors 340 and 344 correspond to the conductors over which the toll operator receives the incoming call.

Fig. 2 shows the selector S, which corresponds to selector S shown in Fig. 4 of said patent, and an outgoing repeater accessible to the banks of the selector S which is operated on outgoing toll calls from the toll board of Fig. 1. A two-conductor trunk line comprising conductors 575 and 576 extends from this repeater to the distant toll exchange. This repeater normally connects the two-conductor trunk line to the incoming selector repeater shown in Fig. 3.

Fig. 3 shows an incoming selector repeater normally accessible over the two-conductor trunk line from the distant toll exchange by way of normal connections in the repeater shown in Fig. 2, and is taken into use on calls originating from the distant toll exchange. This selector repeater is of the well known type of Strowger vertical and rotary switch which operates its shaft and wipers in a vertical direction to select a group and then automatically rotates the shaft and wipers until an idle switch in the selected group is reached. This selector repeater has access to toll transmission selectors such as are diagrammatically shown in Fig. 4 and more fully shown in Fig. 7 of Patent 1,883,589, and repeat impulses thereto.

Fig. 4 diagrammatically shows a toll transmission selector TTS and a toll connector T corresponding to the toll transmission selector TTS and the toll connector C shown in Figs. 7 and 8 of Patent 1,883,589. Switch TTS has access to groups of connectors such as C and these connectors have access to subscribers' lines such as T.

Fig. 5 shows a toll selector repeater in the distant toll exchange terminating the trunk line conductors 575 and 576. This toll selector repeater is also of the well known Strowger vertical and rotary type and has access to selectors, such as selector S1 shown in Fig. 6, by way of its wipers. A portion of the circuits of this toll selector repeater terminate in the toll board, shown to the right, and is used by the toll operator in this distant toll exchange to extend outgoing toll calls over conductors 575 and 576.

Fig. 6 diagrammatically shows selectors S1 and connector C1 and a subscriber's line T1. The selector S1 and connector C1 are similar to the selectors and connectors shown and described in the Wicks Patent 1,315,444, issued September 9, 1919. Incoming calls to this distant toll exchange are extended over the trunk line conductors to the toll selector repeater of Fig. 5 which operates and repeats impulses to the selector S1 and connector C1 to cause these switches to extend and complete calls to the called subscriber's line. Outgoing calls from this distant exchange are

extended from the toll board of Fig. 5 through the toll selector repeater over the trunk line conductors 575 and 576 to the incoming selector repeater of Fig. 3 and through the toll transmission selector TTS and connector C to the called line.

Having briefly described the apparatus comprising the invention, the detailed description of the operation involved in setting up the various calls will now be given.

10 Outgoing calls

Calls to the operator's position of Fig. 1 are received and handled in the same manner as described in the Crocker et al. Patent 1,883,589. In 15 order to describe an outgoing call it will be assumed that the toll operator has received and answered a call and that the calling party is now connected to the trunk comprising conductors 340 and 344. After the toll operator has ascertained 20 that the toll call is to be extended to subscriber T1 in the distant toll exchange, the key K3 is operated.

In response to the operation of key K3 in Fig. 1 relay 351 is energized over the following circuit: 25 from ground by way of contact 234, spring contacts 389 of key K3, and through the upper winding of relay 351 to battery. Relay 351, upon energizing, at contacts 360 completes a locking circuit for itself and an energizing circuit for relays 352 and 203 as follows: from ground through the winding of relay 203, conductor 212, springs 392 of key K3, winding of relay 352, contact 360, and the lower winding of relay 351, to battery. At contacts 358 and 363 relay 351 disconnects 30 the incoming trunk conductors 340 and 344 and prepares a point in the dialing circuit for extending the connection. Relay 352, upon energizing, at contact 366 prepares a circuit for relay 354, and at contact 367 prepares a locking circuit for relays 203, 351, and 352 independent of key K3. Relay 203, upon energizing, at contacts 230 and 231 connects up the operator's headset and at contacts 234 opens the original energizing circuit of relay 351, which relay, however, is locked energized over its lower winding as previously described. The toll operator may now converse with the calling subscriber by way of contacts 230, 231, conductors 223 and 220, contacts 357 and 355, and over conductors 340 and 344 to the calling party. After receiving the telephone number of the desired called party, the toll operator will operate the calling device D and dial the digits of the called subscriber's line.

In response to setting the calling device D in accordance with the first digit of the off-normal springs 270 and 271 close to complete the circuit for energizing relays 208, 206 and 205. The circuit for energizing relay 208 extends from ground through off-normal springs 270 and 271, and through the winding of relay 208, to battery. The circuit for energizing relays 206 and 205 extend from ground through off-normal springs 270 through the windings of relays 206 and 205 in series, to battery. Relay 208, upon energizing, at contacts 253 short circuits relay 207, at contact 254 connects an additional ground for maintaining relays 206 and 205 energized, and at contact 255 completed an obvious circuit for energizing relay 209. Relays 206 and 205, upon energizing, at contacts 237 and 240 opens the loop through the operator's position and at contacts 248, 238, 250 and 239 prepares a point in the impulsive circuit. At contact 249 relay 206 completes the circuit for energizing relays 354 and 355 as follows: from ground by way of springs

258 of key K, contact 249, spring contacts 388 of key K3, contact 366, upper winding of relay 354, and through the lower winding of relay 355 to battery. Relay 209, upon energizing, at contact 242 completes the circuit for lighting the dial pilot lamp L and at contact 257 completes the locking circuit of relays 203, 351, and 352, which locking circuit is independent of springs 392 of key K3. Relay 354, upon energizing, at contacts 371 completes a locking circuit for relay 355, and at contacts 372 completes a locking circuit through its lower winding to ground at key K4. Relay 355, upon energizing, at contacts 376 completes a locking circuit for itself through its upper winding from ground by way of springs 259 of key K, conductor 214, springs 390 of key K3, contacts 371, contacts 376, and through the upper winding of relay 355, to battery. At contact 375 relay 355 grounds the holding conductor 381 extending to the selector S, at contact 377 prepares a point in the circuit of the supervisory relay 356, and at contacts 374 and 378 completes the circuit for the line relay 402 in selector S, as follows: from ground, through the lower winding of line relay 402, contact 418, conductor 383, contact 378, contact 364, contact 239, contact 250, to the dial impulse springs 272, contact 253, contact 248, contact 238, conductor 222, contact 359, contact 374, conductor 380, contact 411, and through the upper winding of line relay 402 to battery. The operation of line relay 402 in selector S operates the release relay (not shown) and prepares this selector for operation as described in the Crocker et al. patent.

During the return of the dial to normal the impulse springs 272 are interrupted a number of times corresponding to the digits dialled. Each time the impulse springs 272 are opened the line relay 402 deenergizes to cause the selector S to operate its shaft and wipers in a vertical direction opposite the desired group of bank contacts. After selecting the desired group of bank contacts the selector S automatically rotates its shaft and wipers to select an idle trunk in this group. For the purpose of describing this invention it will be assumed that the outgoing repeater in Fig. 2 is seized by the selector S.

When the dial is fully returned to its normal position the dial shunt springs 270 and 271 open, thereby opening the circuit of slow-to-release relay 208. Due to its slow release characteristics indicated by the copper rectangle at the lower portion of relay 208, this relay releases after an interval. At contact 253 relay 208 momentarily bridges relay 207 across the trunk conductors 503 and 506 before relays 206, 209, and 205 are released. Relay 207 is now operated in series with relays 520 and 530 over the following circuit: from ground through the lower winding of line relay 530, contact 517, lower left-hand winding of repeating coil RC, conductor 506, bank contact and wiper of selector S, contact 417, conductor 383, contacts 378, 364, 239, 250, 272, through the winding of relay 207, contacts 248, 238, 359, and 374, conductor 380, contact 412, upper wiper and bank contact of selector S, conductor 503, upper left-hand winding or repeating coil RC, contact 511, and through the windings of relays 520 and 530, to battery. At contact 521 relay 207 maintains relays 206 and 205 energized and at contact 252 maintains relay 209 energized by way of ground extending through springs 258 of key K.

When the selector S switches through in the well-known manner, upon the seizure of the re- 75

repeater in Fig. 2, the switching relay 401 is operated and completes the previously traced circuit for relays 520 and 530. The switching relay 401, at contact 416, grounds hold conductor 504 to make this outgoing repeater busy to other selector switches, and at contact 413 completes a circuit for energizing relay 356 and relay 540 in series, as follows: from ground through the upper low resistance winding of relay 540, contact 501, conductor 505, bank contact and wiper of selector S, contact 413, conductor 382, contact 377, and through the winding of relay 356 to battery. Relay 356, upon energizing, at contact 373 lights the supervisory lamp L4 at the operator's position. Line relay 530, upon energizing over the above-traced circuit, at contact 531 prepares a point in the talking circuit and impulse repeating circuit, and at contact 532 completes an obvious circuit for energizing relay 560. Relay 520, being marginal, will not energize in series with the high resistance winding of relay 207, and therefore relay 520 only energizes at a time when relay 207 is short circuited via contact 253. Relay 540, upon energizing over the above-traced circuit, at contact 541 closes a multiple ground for maintaining relay 560 operated, at 542 prepares a point in the circuit of relay 570, and at 543 prepares a point in the locking circuit for relay 510. Relay 560, upon energizing, at contacts 561 and 563 connects the outgoing repeater to the outgoing trunk conductors 575 and 576 extending to the distant exchange, and disconnects the incoming selector repeater shown in Fig. 3. At contact 562 relay 560 completes a circuit through the upper winding of electropolarized relay 500 to prepare that relay for operation. It should be mentioned at this time that a circuit is completed through the lower winding of electropolarized relay 500 as follows: from ground through the upper winding of differential ring relay 840 in Fig. 5, upper winding of line relay 830, back contact 822, normally closed contacts controlled by armature 812, lower left-hand winding of repeat coil RC, conductor 576, contact 563, lower right-hand winding of repeat coil RC in the outgoing repeater of Fig. 2, lower winding of electropolarized relay 500, upper right-hand winding of repeat coil RC, contact 531, contact 561, trunk conductor 575, upper left-hand winding of repeat coil RC in Fig. 5, normally closed contacts controlled by armature 811, back contacts 823, and through the lower windings of line relay 820 and differential ring relay 840, to battery. Electropolarized relay 500 will not operate over this circuit because the two windings oppose each other.

When the dial is again operated off normal preparatory to dialling the second digit, relay 208 is again energized by way of springs 271 and this relay at contact 253 short circuits relay 207 causing relay 207 to release as well as causing the operation of marginal relay 520 in the outgoing repeater. Relay 520, upon energizing, at 521 completes the circuit for operating relay 570 by way of contact 542. Relay 570, upon operating, at contact 571 prepares a point in the circuit for short-circuiting the right-hand windings of the repeating coil RC and the lower winding of relay 500, and at contact 572 completes the circuit for energizing relay 550. The circuit for energizing relay 550 may be traced as follows: from ground by way of back contact 513, front contact 572, through the winding of relay 550, back contact 514, and through resistance 516 to battery. At 551 relay 550 opens a point in the circuit of the

repeating coil RC, at 552 prepares a point in the energizing circuit of relay 510, and at 553 completes the short circuit around the right-hand windings of the repeating coil RC and the lower winding of relay 500 to improve the impulsing circuit extending over the trunk conductors 575 and 576 to the distant exchange. When the calling device D is returning to its normal position, the impulse springs 272 interrupt the circuit of relays 520 and 530, and the latter relay at contact 531 interrupts the loop extending through the windings of the line relay 830 and ring relay 840, as previously described. The improved impulsing circuit instead of extending through the windings of repeating coil RC and the lower winding of relay 500, extend by way of conductor 576, front contact 563, contact 553, front contact 571, impulse repeating contact 531, front contact 561, to conductor 575.

Line relay 830 in the toll selector repeater of Fig. 5 operates over the previously traced loop circuit over conductor 575 and 576 but ring relay 840, being differential, will not operate. Line relay 830, upon energizing, at front contact 831 completes an obvious circuit for the slow-to-release relay 850, and at contact 832 prepares a point in the circuit for repeating impulses to the subsequent switches. Relay 850, upon energizing, at contact 851 and its bank contact opens a point in the circuit to the release magnet 844, 30 and at its front contact prepares a point in the circuit for relays 880 and 890. At contact 852 relay 850 prepares a point in the circuit for the upper winding of relay 810 for supervisory purposes, at contact 853 removes the short circuit from around the resistance R1, and at contact 854 prepares a point in the circuit for relay 800 and vertical magnet 897.

Each time line relay 530 in the outgoing repeater interrupts the loop circuit over the trunk conductors 575 and 576, line relay 830 in the toll selector repeater deenergizes to operate relay 800 and vertical magnet 897. The circuit for energizing relay 800 extends from ground by way of back contact 831, contact 854, and through the winding of relay 800 to battery. The circuit for operating the vertical magnet 897 extends from ground by way of back contact 831, contact 854, back contact 824, contact 894, and through the winding of vertical magnet 897, to battery. Vertical magnet 897 follows the impulses and steps the shaft and wipers in a vertical direction opposite the group of bank contacts corresponding to the digit dialled. On the first vertical step of the shaft the off-normal springs 843 close to prepare the circuit for the release magnet 844, and at vertical off-normal springs 885 prepares a point in the circuit for stepping relay 880. Relay 800 is maintained energized during the impulsing, and at contacts 801 and 803 completes the circuit for energizing stepping relay 880, and short circuits switching relay 890. At contact 802 relay 800 opens a point in the circuit to the rotary magnet 884, and at contacts 804 and 805 short-circuits the left-hand windings of repeating coil RC to improve the impulsing circuit.

The circuit for energizing relay 880 may be traced as follows: from ground by way of front contact 851, contacts 803 and 801, contact 892, 70 vertical off-normal contact 885, and through the winding of stepping relay 880 to battery. The short circuit for switching relay 890 may be traced from the left-hand terminal of this relay by way of interrupter contact 883 of rotary mag- 75

net 884, contact 892, contacts 801 and 803, to the right-hand terminal of relay 890. Relay 880, upon energizing, at contact 881 prepares a point in the circuit to the rotary magnet 884, and at contact 882 completes a locking circuit for itself by way of the rotary magnet interrupter contacts 883 and vertical off-normal springs 885, as well as completing a short circuit from ground at armature 882, through relay 890 to ground at front contact 851. Due to the slow release characteristic of relays 880 and 850, these relays are maintained in operated position during the dialing. After the impulsive period line relay 830 is maintained energized to maintain relay 850 in energized position and shortly thereafter slow-to-release relay 880 deenergizes. At contacts 804 and 805 the short circuit from around the left-hand windings of the repeating coil RC is removed and at contact 802 rotary magnet 884 is energized over the following circuit: from ground, by way of front contact 851, contact 882, contact 881, and through the winding of rotary magnet 884, to battery. The rotary magnet 884 energized and rotates the wipers one step and near the end of its stroke opens the interrupter contact 883 to open the locking circuit of relay 880 which accordingly releases. Relay 880, upon releasing, at contact 881 opens the circuit of rotary magnet 884 to cause its deenergization, and at contact 882 removes the short circuit from around switching relay 890. The wipers of the selector repeater are now in engagement with the first set of bank contacts in the selected group and the operation of the toll selector repeater depends upon the idle condition of the first selector such as S1 in the group.

In case this selector is in use, then ground is encountered by test wiper 863 and stepping relay 880 is energized as follows: from ground on the bank contact engaged by test wiper 863, back contact 893, interrupter contact 883 of rotary magnet 884, vertical off-normal springs 885, and through the winding of stepping relay 880 to battery. The ground connection engaged by test wiper 863 likewise maintains the switching relay 890 short circuited to prevent its operation on busy connections. The operation of stepping relay 880 again completes the circuit for rotary magnet 884 at contact 881, and again completes a locking circuit for itself at contact 882 as well as short circuiting switching relay 890. The rotary magnet 884 reoperates and rotates the wipers another step into engagement with the second bank contact and again at contact 883 releases relay 880. This interaction between rotary magnet 884 and stepping relay 880 continues until wiper 863 no longer engages a grounded bank contact, at which time the short circuit is removed from switching relay 890.

Assuming now that the selector S1, Fig. 6, is the first idle selector accessible in this ground in which case no ground connection will be connected to conductor 815 and the switching relay 890 will not be short circuited. Switching relay 890 energizes in series with stepping relay 880, the latter relay being marginal will not energize in series with switching relay 890 because of its high resistance. The circuit for energizing switching relay 890 may be traced as follows: from ground by way of front contact 851 through the winding of switching relay 890, interrupter contact 883 of rotary magnet 884, vertical off-normal springs 885, and through the winding of stepping relay 880 to battery. Switching relay 890, upon operating, at contacts 891 and 896,

switches the talking conductors through to conductors 814 and 817 terminating in the selector S1 of Fig. 6. At contact 892 relay 890 opens a point in the initial energizing circuit of relay 880, at contact 893 grounds test wiper 863 to make selector S1 busy, at contact 894 opens the circuit to the vertical magnet 897, and at contact 895 completes the energizing circuit for the line relay (not shown) in selector S1 from grounded armature 852 by way of wiper 864 of conductor 816.

The subsequent digits transmitted by the repeater of Fig. 2 operate relays 830 and 800 as before, causing relay 800 to short circuit the left-hand windings of the repeating coil RC, while at contact 882 repeats impulses to the line relay in the selector S1. The selector S1 and connector C1 in Fig. 6 are somewhat similar to the selector and connector shown in the Wicks patent previously referred to and are operated in the manner set forth therein to connect with the called line.

After the toll operator has completed dialing the called subscriber's number, off-normal dial springs 270 and 271 of the calling device D open and restore relay 208 after an interval, as previously described. Contact 253 again bridges relays 207 across the trunk conductors 389 and 383 before relays 206, 209 and 205 release. Due to the high resistance of relay 207, relay 520 in Fig. 2 is released. Relay 207, however, energizes as previously described, and at contact 252 maintains relay 209 energized and at contact 251 maintains relays 206 and 205 in operated position. In the outgoing repeater relay 520 deenergizes since it is marginal in series with the high resistance relay 207, but line relay 530 is maintained energized over the previously traced loop circuit. Relay 520, upon releasing, at contact 521 opens the circuit for relay 570. Relay 570 has not released previously because the chain of relays, namely 208, 520 and 570 are slow releasing relays and the interval between digits, when the dial is at normal, is of insufficient duration to finally open the circuit of relay 570 long enough to permit its release; it being understood that first slow relay 208 must fully release, then slow relay 520 must fully release to hold open the circuit of slow relay 570 for a predetermined interval. During the normal operation of the dial by the operator, the dial is not in normal position, between digits, for a sufficient length of time to cause relay 570 to release. After completion of dialing, however, the dial does remain in normal position and the circuit to relay 570 is held open long enough to cause its release. Relay 570, upon releasing at front contact 571 removes the short circuit from around the right-hand windings of repeating coil RC and the lower winding of relay 500, and at front contact 572 momentarily opens the circuit of slow-to-release relay 550, which, however, is maintained in operated position for a short interval due to its slow release characteristics. At back contact 571 relay 570 completes a circuit for operating the differential ringing relay 840 in the toll selector repeater of Fig. 5 in order to initiate the ringing operation, and at contact 572 completes a circuit for energizing relay 510. This circuit may be traced as follows: ground by way of back contact 513, back contact 572, contact 552, and through the winding of relay 510 to battery. At contacts 511 and 517 relay 510 opens the circuit of relays 207 and 530. Relay 207 deenergizes but relay 530 is maintained in operated position in series with

relay 510 as follows: from ground through the lower winding of line relay 530, spring 518, contact 543, and through the winding of relay 510 to battery. At contact 513 relay 510 opens the original energizing circuit of relay 510 and at 514 prepares a point in a new circuit for relay 550. Relay 550 is now connected to make contacts 513 and 514 and 515 to conductor 506 so that relay 550 may be operated in case the operator desires to re-ring the called subscriber. Relay 550, however, deenergizes when its circuit is opened after an interval at contacts 513 and 514. At contact 551 relay 550 completes the circuit for the left-hand winding of repeating coil RC in order to complete the talking circuit, at contact 552 opens the original energizing circuit of relay 510 now locked in series with relay 530, and at contact 553 disconnects negative battery connected to resistance 564 from conductor 576.

Relay 207 deenergizes in response to the operation of relay 510, and at contact 251 opens the circuit of relays 206 and 205 and at contact 252 opens the circuit of relay 209. Relay 206, upon deenergizing, at contact 248 and 250 disconnects the calling device from the trunk conductors 503 and 506 and at contact 249 opens a point in the original energizing circuit of relay 355 and 354 which relays are, however, maintained in operated position over their locking circuits. Slow-to-release relay 209, upon deenergizing, at contact 242 extinguishes the dial pilot lamp L and at contact 251 opens the locking circuit of relays 203, 351, and 352. Relay 205 likewise deenergizes after an interval and at contacts 231 and 240 connect up the operator's headset.

Returning now to the outgoing repeater and at a time when relay 570 has deenergized and before relay 550 is fully restored, negative battery extending by way of resistance 564, back contact 571, and contact 553 is momentarily connected to trunk conductor 576 by way of front contact 563. Due to this momentary connection of negative battery to conductor 576 differential ringing relay 840 is operated. Line relay 830, however, is maintained in operated position over the loop circuit extending from the outgoing repeater over the trunk conductors 575 and 576 but the momentary connection of this negative battery potential through resistance 564 to conductor 576 creates an unbalanced condition in the trunk loop with the result that the differential ringing relay 840 is momentarily operated. Relay 840, upon operating, at contacts 841 and 842 connects generator across the trunk conductors 814 and 817 to cause the operation of the ringing relay (not shown) in the selector S which ringing relay in turn causes the ringing of the called subscriber as described in the Wicks patent previously referred to. When the called party answers relay 810 is energized over the called subscriber's loop by way of conductors 814 and 816, wipers 862 and 865, contacts 891 and 893, right-hand winding of the repeating coil RC, contact 852, and through the windings of relay 810 to ground and battery. Relay 810, upon energizing, at contacts 811 and 812, reverses battery over the trunk conductors 575 and 576 to cause the operation of electropolarized relay 500 in the outgoing repeater.

Relay 500, upon energizing, at contact 501 removes the short circuit from around the high resistance lower winding of relay 540, thereby reducing the current flow over conductor 505 sufficiently to cause the release of supervisory relay 356 at the toll operator's position. At con-

tact 379 supervisory relay 356 extinguishes the supervisory lamp L4, thereby indicating to the toll operator that the called subscriber has responded. The toll operator may talk to either the calling or the called party as described in the Crocker et al. patent, and when satisfied that the proper toll connection has been completed she may withdraw from the connection by restoring the key K3. At spring 391 of key K3 a new holding circuit is completed for relay 355 and at contact 392 the holding circuit of relays 203, 351, and 352 is opened to cause the release of these relays. Relay 203, upon releasing, at contacts 230 and 231 disconnects the operator's headset and relay 351, upon releasing, at contacts 353 and 355 connects the called line to trunk conductors 340 and 344 and the calling line connected thereto.

In case the called line were busy when called, then the busy relay in connector C1 operates and connects interrupted ground to conductor 814, thereby intermittently operating relay 810 over the following circuit: from ground through the interrupter and make contacts of the busy relay in connector C1 over the upper bank contact and wiper of selector S1, conductor 814, wiper 862, contacts 891 and 841, upper right-hand winding of repeating coil RC, contact 852, and through the upper winding of relay 810 to battery. Each operation of relay 810 at contacts 811 and 812 reverses battery over the trunk conductors 575 and 576, thereby causing the intermittent operation of electropolarized relay 500 in the outgoing repeater. Relay 500 at contact 501 intermittently includes and excludes the high resistance lower winding of relay 540 in circuit with relay 356 over conductor 505, thereby causing the intermittent operation of supervisory relay 356 at the toll position. Relay 356 therefore intermittently operates to flash the supervisory lamp L4 by way of contact 379 to indicate to the toll operator that the called line is busy.

After conversation and when the called party hangs up, relay 810 releases and restores the battery connection over trunk conductors 575 and 576 to normal, thereby causing the deenergization and release of electropolarized relay 500 in the outgoing repeater because the current flow in these two windings now oppose each other. When electropolarized relay 500 restores, said relay at contact 501 shorts the lower high resistance winding of relay 540, thereby permitting the supervisory relay 356 in the toll position to energize. The steady energization of supervisory relay 356 causes the steady lighting of the supervisory lamp, thereby indicating to the toll operator that the called subscriber has replaced his receiver.

In case the toll operator desires to re-ring the called party negative battery is connected through contacts 378 and conductor 383 by way of re-ring key RK to operate relay 550 in the outgoing repeater. This circuit may be traced from ground at make contacts 513 and 514, winding of relay 550, contact 515, lower left-hand winding of repeating coil RC, conductor 506, bank contact and wiper of selector S, front contact 417, conductor 383, contact 378, and through the ringing key RK and resistance to battery. At contact 553 relay 550 connects negative battery through resistance 564 and back contact 571 to conductor 576 by way of front contact 563 to cause the reoperation of differential ringing relay 840 in the toll selector repeater of Fig. 5, in the same manner as previously described. Relay 72

840 at contacts 841 and 842 again connects ringing generator across the conductors 814 and 817 to rering the called subscriber.

- When the toll operator receives the disconnect signal by the steady lighting of the supervisory lamp L4, the operator may release the established connection by releasing key K4 to open the locking circuit of relay 354. Relay 354, upon releasing, at contact 371 opens the locking circuit of relay 355 to cause the deenergization of the latter relay. At contacts 374 and 378 relay 355 disconnects the operator's position from the selector S, at contact 375 disconnects ground from conductor 381, and at contact 377 opens the circuit to the supervisory relay 356 and relay 540 in the outgoing repeater. The selector S is restored to normal in the same manner as described in the Crocker et al. patent and relay 540, upon deenergizing, at contact 541 opens the circuit for relay 560 and at contact 543 opens the circuit of relays 510 and 530. Relay 510, upon deenergizing, at contacts 511 and 517 prepares the original circuits of relays 520 and 530, and at contacts 513 and 514 disconnects ground from relay 550 and substitutes a battery connection through resistance 516 therefor. Relay 530, upon deenergizing, at contact 531 opens the loop circuit extending over the trunk to the toll selector repeater of Fig. 5 to cause the deenergization of line relay 830 therein. After an interval slow-to-release relay 560 deenergizes and at contacts 561 and 563 connects the trunk conductors 575 and 576 to the incoming selector repeater of Fig. 3.
- In the distant exchange line relay 830 deenergizes when the loop circuit thereto is opened over the trunk conductors and at front contact 831 opens the circuit to slow-to-release relay 850. At the back contact 831 relay 830 momentarily operates relay 800 which is without effect at this time, and at contact 832 disconnects ground from conductor 816 to release the line relay in selector S1. Release relay 850, upon deenergizing after an interval, at contact 851 opens the circuit of switching relay 890, and removes ground from wiper 863 and from conductor 807. At back contact 851 relay 850 completes a circuit for energizing the release magnet 844 by way of vertical off-normal springs 843, at contact 852 disconnects the upper winding of relay 810 from the toll board and selector S1, at 853 reestablishes the short circuit around resistance R1, and at contact 854 opens the circuit to relay 800 which releases after an interval. Switching relay 890 likewise restores to normal. The release magnet 844 upon energizing releases the switch shaft and wiper and the vertical off-normal springs 885 and 843 open, the latter off-normal springs opening the circuit to the release magnet 844, which thereupon deenergizes. The toll selector repeater of Fig. 5 is now in normal position, and may be used on subsequent calls. The succeeding switches such as selector S1 and connector C1 in Fig. 6 release in the manner described in the Wicks patent previously referred to. The entire connection is now released and may be used on subsequent calls.

Incoming calls

- Having described a toll connection extending from the toll position in Fig. 1 over the trunk line to the distant exchange shown in Figs. 5 and 6, a description of a toll connection originating at the toll board of the distant exchange, Fig. 6, over the trunk line conductors 575 and 576

through the incoming selector repeater, the toll transmission selector TTS, and connector C to a subscriber's line such as T will now be given. For this purpose, it will be assumed that a call has come in to the operator's position in the toll board in Fig. 6, and that the toll connection is to be completed to the called subscriber's line T in Fig. 4. The toll operator after ascertaining that subscriber T is the desired called subscriber grounds conductor 888 extending from the toll board to the toll selector repeater. In response to grounding conductor 888 relay 870 is energized over the following circuit: from grounded conductor 808, contacts 861 and 853 and through the winding of relay 870 to battery. At contact 871 relay 870 connects the lower winding of relay 810 to conductor 806 extending to the toll board; at conductor 872 prepares a circuit for relay 860, and at contact 873 completes the circuit for operating relay 820. Relay 820, upon energizing, at contact 821 connects grounded armature 851 to conductor 807 extending to the toll board. Through back contacts 822 and 823 relay 820 disconnects the windings of line relay 830 and differential relay 840 from the trunk conductors 575 and 576, and at front contacts 822 and 823 connects the rectifier 863 in bridge across these trunk conductors as well as preparing a circuit for relay 860. At front contact 824 relay 820 prepares the circuit for relay 800.

Relay 610 in the incoming selector repeater of Fig. 5 is now energized over a loop circuit as follows: from ground, through the lower winding of relay 610, normally closed springs controlled by contact 603, conductor 574, back contact 563, conductor 576, lower left-hand winding of repeating coil RC of the toll selector repeater of Fig. 5, normally closed springs controlled by contact 812, front contact 822, rectifier 863, contact 872, front contact 823, normally closed springs controlled by contact 811, upper left-hand winding of repeating coil RC, conductor 575, back contact 561, conductor 573, normally closed contacts controlled by contact 601, and through the upper winding of relay 610 to battery. It will be noted that the rectifier 862 and the winding of relay 860 is also bridged across this loop circuit, but the rectifier 862 blocks current flow through the winding of relay 860. The blocking effect of rectifier 862 is such that relay 860 will only operate when the current is reversed from normal over the trunk conductors 575 and 576.

Relay 610 in the incoming selector repeater of Fig. 3 operates over this loop circuit including the rectifier 863 and at contact 611 completes the circuit for slow-to-release relay 620. At contact 612 relay 610 prepares a point for repeating impulses to the toll transmission selector after the incoming selector repeater has switched through. Relay 620, upon energizing, at contact 621 grounds conductor 504 to make the outgoing repeater and inter-exchange trunk line busy to selectors such as selector S. At contact 622 prepares a point in a circuit for the vertical magnet 616, relay 630 and relay 660, at contact 623 relay 620 prepares the circuit for switching relay 680, for rotary magnet 643 and opens the circuit to the release magnet 615.

The toll operator now dials the digits of the called subscriber's line, thereby disconnecting ground from conductor 808 for each impulse to be transmitted. Relay 870 follows the impulses and at contact 872 opens the loop circuit extending over the trunk conductors to cause the line relay 610 in the incoming selector repeater to

operate a corresponding number of times. At the back contact 873 relay 870 completes the circuit for energizing relay 800 by way of front contact 824. It will be understood that the slow-to-release relay 820 is maintained in operated position during the dialling period. Relay 800, upon energizing, at contacts 804 and 805 short circuits the left-hand winding of the repeating coil RC to improve the impulsing circuit over the trunk conductors 575 and 576. Relay 800 is likewise slow to release and is maintained in operated position only during the dialling period. After the dialling of each digit relay 820 is maintained in operated position, while relay 800 releases after an interval to remove the short circuit from around the left-hand winding of the repeating coil RC.

Line relay 610 in the incoming selector repeater follows the impulses transmitted by contact 872 and on each deenergization thereof completes a circuit for operating the series relay 630 and vertical magnet 616 as follows: from ground by way of back contact 611, contact 622, back contact 684, winding of slow-to-release series relay 630, and through the winding of vertical magnet 616 to battery. The series relay 630, upon energizing, at contact 631 opens a point in the circuit to rotary magnet 643 and prepares a point in the circuit to stepping relay 640. Vertical magnet 616 operates the shaft and wipers one step in a vertical direction for each impulse received to position the wipers of the incoming selector repeater opposite the desired group of toll transmission selectors.

On the first vertical step of the shaft vertical off-normal springs 613 prepares a point in the circuit for release magnet 615 and vertical off-normal springs 632 close to complete an energizing circuit for stepping relay 640 by way of contacts 631 and 623. Stepping relay 640, upon energizing, at contact 641, prepares a point in the circuit for rotary magnet 643 and at contact 642 completes a locking circuit for itself by way of interrupter contacts 654 and vertical off-normal springs 632.

After the last impulse of the digit just transmitted relay 610 is maintained in operated position with the result that the slow-to-release series relay 630 deenergizes after an interval. It should also be mentioned at this time that the slow-to-release relay 620, due to its slow release characteristics, is maintained in operated position during the dialling period, while the series relay 630 is maintained in operated position only during the dialling period and deenergizes shortly after the last impulse of the digit. When series relay 630 deenergizes rotary magnet 643 is energized over the following circuit: from ground, by way of front contact 623, normally closed springs controlled by contact 631, contact 641, and through the winding of rotary magnet 643 to battery. Rotary magnet 643 energizes and rotates the wipers 693 to 696 into engagement with the first set of bank contacts in the selected group. The rotary magnet near the end of its stroke opens the locking circuit of stepping relay 640 at interrupter contacts 654 to cause the stepping relay to deenergize. It should be mentioned that the switching relay 680 is short circuited by contacts 631 when the series relay 630 is operated by way of cam springs 686 and interrupter springs 654, and after deenergization of series relay 630 switching relay 680 is likewise short circuited from ground by way of front contact 623, cam springs 686, and contact 642 of the energized

stepping relay 640. These short circuits are provided to prevent the premature energization of switching relay 680. Stepping relay 640 deenergizes when the rotary magnet interrupts its locking circuit at 654, thereby at contact 641 opening the circuit to the rotary magnet 643, which likewise deenergizes. At contact 642 the short circuit from around switching relay 680 is removed and further operation of the stepping relay and rotary magnet is dependent upon the busy condition of the contact engaged by the test wiper 694. If the toll transmission selector is busy then the bank contact engaged by test wiper 694 will be grounded with a result that the stepping relay 640 is energized over the following circuit: from grounded bank contact, test wiper 694, back contact 683, interrupter contact 654 of the rotary magnet 643, vertical off-normal springs 632, and through the winding of relay 640 to battery. Ground at the test wiper 694 likewise short circuits the switching relay 680 to prevent its energization. Relay 640, upon reoperating, at contact 641 again operates the rotary magnet 643 and at contact 642 again short circuits the switching relay 680 as well as completing a locking circuit for itself. The rotary magnet again rotates the wipers an additional step and at interrupter contacts 654 again opens the circuit of stepping relay 640. Stepping relay 640, upon deenergizing, at 641 opens the circuit of rotary magnet 643 which accordingly deenergizes. Relay 640 at 642 opens the short circuit from around switching relay 680 to enable this relay to energize providing the test wiper 694 is not in engagement with a grounded bank contact. This inter-action between the stepping relay 640 and rotary magnet 643 continues until the test wiper 694 no longer engages a grounded bank contact with the result that the short circuit is removed from around the switching relay 680, whereupon relay 680 is energized in series with the switching relay 640. The circuit for energizing relay 680 may be traced as follows: from ground by way of front contact 623, cam springs 686, winding of relay 680, interrupter contact 654, vertical off-normal contacts 632, and through the winding of relay 640 to battery. Due to the high resistance of the switching relay 680, stepping relay 640 is not operated over this circuit. Switching relay 680, upon energizing, at contacts 681 and 685 completes a circuit for energizing relay 650 and line relay 707 of the toll transmission selector TTS as follows: from ground by way of contact 723, resistance 710, lower left-hand winding of repeating coil RC of toll switch TTS, conductor 435, wiper 696, conductor 689, contacts 685 and 612, lower right-hand winding of repeating coil RC of the incoming selector repeater, upper winding of relay 650, upper right-hand winding of repeating coil RC, contact 681, conductor 686, wiper 693, conductor 438, upper left-hand winding of repeating coil RC of switch TTS, resistance 769, contact 716, and through the upper winding of line relay 707 to battery. At contact 682 relay 680 prepares a circuit for relay 690, at back contact 683 opens the rotary test circuit and at front contact 683 connects grounded contact 623 to test wiper 694 to mark the toll transmission selector TTS busy to other switches having access thereto. At front contact 684 switching relay 680 prepares the circuit for relay 660, and at back contact 684 opens the circuit to relay 630 and vertical magnet 616. Relay 650, upon energizing, at front contact 651 completes an obvious circuit for energizing relay 75.

670 by way of resistance 655, at contact 652 prepares a locking circuit through its lower winding and at contact 653 completes a shunt around contact 673 for controlling the operation of relay 600. Relay 670, upon energizing, at contact 671 opens a point in the repeating coil circuit, at contact 672 prepares a point in the circuit for connecting negative battery potential to the lower talking conductor for the purpose of starting the 10 ringing operation, and separates the contacts 673 which is without effect at this time, since contacts 653 are now closed.

In response to the subsequent digits dialled by the toll operator line relay 610 follows the loop 15 pulses transmitted by relay 670, and at contact 612 repeats these impulses to line relay 707 in the toll transmission selector TTS. Each time line relay 610 deenergizes, contacts 611 completes a circuit for slow-to-release relay 690 by 20 way of contacts 622 and 684. Relay 690 is maintained in operated position during the dialling period and at contact 662 completes an obvious circuit for maintaining relay 670 in energized position independent of relay 650. At contact 25 663 relay 660 completes an obvious locking circuit for relay 650 and at contact 661 shorts-circuits the upper winding of relay 650 and the right-hand winding of repeating coil RC to improve the impulsing circuit. The impulse repeating circuit for line relay 707 of the toll transmission selector TTS now includes the following circuit: from ground by way of contact 723, resistance 770, lower right-hand winding of repeating coil RC, conductor 435, wiper 696, contacts 30 685 and 612, 661, 681, wiper 693, conductor 438, upper left-hand winding of repeating coil RC, resistance 769, contact 716, and through the upper winding of line relay 707 to battery. After each series of impulses or after each digit, 35 relay 660 deenergizes to remove the short-circuit from around the right-hand winding of repeating coil RC of the incoming selector repeater and the winding of relay 650 at contact 661 and at contact 662 opens the substitute circuit for relay 670 which, however, is still maintained energized over its original energizing circuit.

The line relay 707 in the toll transmission selector TTS and the relays (not shown) in the connector C operates in the same manner as 40 described in the Crocker et al. patent in response to the digits dialled to extend the connection to called line T.

In case the called line T is busy, relay 701 in the toll transmission selector TTS is operated, 45 and relay 703 is intermittently operated thereafter to intermittently disconnect and connect ground to conductor 436 as described in the Crocker et al. patent. When relay 701 first energizes contact 724 closes the circuit to maintain relay 707 in operated position, and to complete 50 a circuit for energizing relay 690 as follows: from ground through the lower winding of line relay 707, contact 723, resistance R, contact 724, conductor 436, wiper 695, conductor 688, contact 682, and through the winding of relay 690 to battery. The energization of relay 701 in the toll transmission selector TTS, at contacts 55 716 and 722 opens the circuit for energizing relay 650, whereupon relay 650 deenergizes after a short interval. Relay 690, upon energizing over the above-traced circuit, at contacts 691 and 692 prepares a circuit for supervisory relay 600, but this relay does not operate due to the bridge circuit which does not permit sufficient current 60 flow due to the balanced condition present in

this bridge circuit; that is, the ground connection from contact 692 through resistance 614 to one terminal of relay 600 balances the ground connection from the lower winding of relay 707, through resistance R to the other terminal of relay 600. Relay 600, due to this balanced circuit condition, will not energize until the ground connection extending through the lower winding of relay 707 is open. Relay 650, upon deenergizing, at front contact 651 opens the circuit 10 to slow-to-release relay 670, and at back contact 651 momentarily connects negative battery potential through the resistance 655 to conductor 435 to operate ringing relay 704, which, however, is only effective if the called line is found 15 idle. Relay 650 also at contact 653 opens the circuit to supervisory relay 600. Relay 670, due to its slow release characteristics, releases after an interval, and at contact 671 closes a point 20 in the circuit of the left-hand windings of the repeating coil to permit transmission of busy tone, at contact 672 disconnects the negative battery potential from conductor 435 to release the ringing relay 704 and at contact 673 recloses the circuit to relay 600. When relay 703 in the toll 25 transmission selector TTS is operated, contact 723 disconnects ground extending through the lower winding of line relay 707 from one terminal of relay 600, thereby upsetting the balanced bridge circuit previously referred to, with the 30 result that relay 600 now operates over the following circuit: from ground by way of contact 692, resistance 614, through the winding of relay 600, contacts 691 and 682, and through the winding of relay 690 to battery. Relay 600 is 35 energized over this circuit and relay 690 is maintained in operated position.

It may be advisable at this time to more fully describe the balanced circuit of relay 600 in order to more fully understand its operation. 40 Relay 600 is connected in bridge of the two upper legs of a so-called Wheatstone bridge. The first, or upper leg of this Wheatstone bridge may be said to extend from ground through the lower winding of line relay 707, contacts 723, resistance 45 R, conductor 436, wiper 695, to conductor 688; the corresponding other upper leg of this Wheatstone bridge may be said to extend from ground by way of contact 692 and resistance 614 to the center point of the bridge; the first lower leg of 50 this bridge may be said to extend from the center point at which the first lower leg terminating in conductor 688, and from thence to contact 682, and through the winding of relay 690 to battery; and the remaining lower leg of this Wheatstone 55 bridge includes the resistance 604 to battery. Relay 600 is bridged across the center point of this bridge circuit by way of the connection to conductor 688, contact 691, and through the winding of relay 690. The combined resistances 60 of the lower winding of line relay 707 and resistance R are equal to the resistance of 614 in the two upper legs, while resistance 604 is equal to the resistance of the winding of relay 690. Now, since relay 600 is bridged across the center points 65 of this bridge circuit, and since the resistances in the two upper legs from the ground connections are equal no current flows with the result that relay 600 does not operate until such time as relay 703 energizes to disconnect the ground connection from the first upper leg. Therefore, on the first operation of relay 703 relay 600 is energized over the circuit previously traced.

Since it was assumed that the called line T was busy, relay 703 is intermittently operated to 75

intermittently open and close the first upper leg connection of this bridge circuit extending through the winding of relay 707. When relay 703 falls back during its intermittent operation contact 729 again closes this first upper leg circuit through the winding of relay 707, with the result that there is no current flow through relay 600 and relay 600 accordingly releases. From the foregoing description it will be seen that relay 600 is intermittently operated by the intermittent operation of relay 703. Each time relay 600 operates, said relay at contacts 601 and 603 reverses battery over the trunk conductors 575 and 576 to operate the supervisory relay 860 in the toll selector repeater of Fig. 5 through the rectifier 862. Since the rectifier 862 is poled in the direction to permit operation of relay 860 when current is reversed over the trunk. Since relay 600 is intermittently operated to intermittently reverse battery over the trunk, relay 860 likewise is intermittently operated. Each time supervisory relay 860 operates said relay at contact 861 removes the short circuit from around resistance R1, thereby increasing current flow over conductor 808 extending to the toll board to cause the supervisory signal in the toll board to flash to indicate the busy condition to the toll operator. Busy tone is also transmitted over the heavy talking conductors and repeating coils to the toll board which also informs the toll operator that the called line is busy.

Assuming now that the called line T is idle instead of busy when called, then relay 701 is operated to release relay 650 and operate 690, as previously described. However, in this case, relay 703 is operated steadily when the called party answers, and therefore does not operate until after the ringing period. Shortly after relay 650 falls back, relay 670 releases and at contact 40 672 closes the circuit for momentarily operating the ringing relay 704 in the toll transmission selector TTS as follows: from ground through winding of ringing relay 704, contact 722, resistance 770, conductor 435, wiper 696, conductor 489, contacts 685 and 614, back contact 661, contact 672, back contact 651, and resistance 655 to battery. Ringing relay 704 operates and causes the ringing current to be transmitted to the called line, after which relay 703 is steadily operated in response to the called party answering, as described in the Crocker et al. patent. Relay 703, upon steadily operating in response to the called party answering, at contact 728 maintains the line relay operated, and at contact 729 disconnects ground from one of the first upper legs of the bridge circuit previously described to cause the operation of relay 600. Relay 600, accordingly energizes and at contacts 601 and 603 steadily reverses battery over the trunk to cause the steady operation of supervisory relay 860 in the toll selector repeater of Fig. 5. The steady operation of supervisory relay 860 at contact 861 removes the short circuit from around resistance R1, thereby causing a steady disconnect signal to indicate to the toll operator that the called party has responded. For example, a relay similar to relay 356 of Fig. 1 may be connected to conductor 808 in the toll board to control a supervisory lamp such as L4. In response to the steady signal the toll operator will connect the calling and called parties after ascertaining that the correct party has answered the call.

After conversation and when the called party hangs up his receiver, relay 703 releases and connects ground through the winding of relay 707

and resistance R to the upper terminal of relay 600, thereby again establishing the balanced bridge circuit to cause the release of relay 600. Relay 600, upon restoring, at contacts 601 and 603 reverses battery over the trunk to normal, thereby by releasing supervisory relay 860. Relay 860, upon deenergizing, at contact 861 short-circuits the resistance R1, thereby increasing the current flow over conductor 808 to bring in the disconnect signal to the toll position.

In case the toll operator desires to rering the called party she may do so by opening the circuit to relay 870 momentarily. The momentary release of relay 870 at contact 872 momentarily opens the loop circuit extending over the trunk conductor to line relay 610 which also momentarily releases. The momentary release of line relay 610 causes the operation of relay 660 over the circuit previously traced. Relay 870 re-energizes after the momentary opening of its 20 circuit, and at contact 872 recloses the circuit over the trunk conductors to line relay 610 which accordingly reenergizes. The reenergization of line relay 610 opens the circuit to relay 660 which accordingly deenergizes after an interval. The 25 momentary operation of relay 660 in the incoming toll selector repeater has caused the operation of slow-to-release relay 670 by way of contact 622, and when relay 660 is deenergized as just described, negative battery potential is again 30 connected to conductor 435 during the release time of slow-to-release relay 670 as follows: from negative battery through resistance 655, back contact 651, contact 672, back contact 661, contacts 612 and 685, conductor 689, wiper 696, conductor 435, lower left-hand winding of repeating coil RC, resistance 770, contact 722, and through the winding of ringing relay 704 to ground. Relay 704 again operates and again initiates the ringing of the called party as described in the Crocker et al. patent.

The release of the connection is under control of the toll operator, who opens the circuit to relay 870 after receipt of the disconnect signal. Relay 870, upon falling back, at contact 871 opens 45 the circuit to relay 810, at contact 872 opens the loop circuit extending over the trunk to release relay 610, at front contact 873 opens the circuit to relay 820, and at back contact 873 momentarily operates relay 800, which is without effect 50 at this time. After an interval slow-to-release relay 820 deenergizes and at contacts 822 and 823 opens the circuit to supervisory relay 860 and reconnects line relay 830 and differential relay 840 to the trunk conductor. At contact 824 relay 820 opens the circuit to relay 800 which deenergizes 55 after an interval.

Line relay 610 in the incoming selector repeater deenergizes and at contact 611 opens the circuit of slow-to-release relay 620 and also re-operates relay 660, causing the reoperation of relay 670, as previously described. After an interval slow-to-release relay 620 deenergizes and at contact 621 disconnects ground from conductor 504 to remove the busy condition from the multiple banks accessible to the selector such as selector S. At contact 622 opens the circuit of relay 660 which deenergizes after an interval. At front contact 623 relay 620 opens the circuit of relay 680 which now deenergizes and also removes ground from wiper 694 and from holding conductor 437, and at back contact 623 completes an obvious energizing circuit for release magnet 615 through the vertical off-normal springs 613. Switching relay 680 accordingly deenergizes and 70 75

at contacts 681 and 685 opens the circuit to wipers 693 and 696. At contact 682 relay 680 opens the circuit to relay 690 which accordingly releases as well as opening the holding circuit 5 of line relay 707 in series with relay 680. At contact 683 relay 680 opens a further point in the holding circuit and reestablishes the rotary test circuit and at contact 684 opens a point in the circuit to relay 680 and prepares the circuit 10 for relay 680 and vertical magnet 616. Relay 690, upon deenergizing, at contacts 691 and 692 opens points in the circuit of relay 690. In response to the disconnection of ground from the holding conductor 437 and the release of line relay 707, the toll transmission selector TTS and connector C release, as described in the Crocker et al. patent. As soon as the wiper shaft of the incoming selector repeater has restored to normal position the vertical off-normal springs 613 15 are opened to open the circuit of release magnet 615. All of the apparatus is now fully released and may be used on subsequent calls.

Having described the invention, what is considered new and is desired to be protected by 20 Letters Patent is set forth in the following claims:

What is claimed is:

1. In a telephone system, a first toll exchange, subscribers' lines terminating in said exchange, 30 an outgoing repeater and an incoming selector repeater in the first exchange, a second toll exchange, subscribers' lines terminating in said second exchange, a two-way two-conductor trunk line interconnecting said exchanges, the two conductors of said trunk line normally connected to said incoming selector repeater by way of said outgoing repeater in the first exchange, a selector repeater terminating said trunk line in the second exchange, means including a toll operator's position in the first exchange for operating said outgoing repeater to disconnect said two conductors of said trunk line from said incoming selector repeater and to operate said selector repeater over said trunk line for extending a toll 40 call to a subscriber's line in the second exchange, and means including a toll board in the second exchange for operating said selector repeater to operate said incoming selector repeater over said trunk line for extending a toll call to a subscriber's line in the first exchange. 50

2. In a telephone system, a first toll exchange, subscribers' lines terminating in said exchange, an outgoing repeater and an incoming selector repeater in the first exchange, a second toll exchange, subscribers' lines terminating in said second exchange, a two-way two-conductor trunk line interconnecting said exchanges, the two conductors of said trunk line normally connected to said incoming selector repeater by way of said outgoing repeater in the first exchange, a selector repeater terminating said trunk line in the second exchange, means including a toll operator's position in the first exchange for operating said outgoing repeater to disconnect said two conductors of said trunk line from said incoming selector repeater and to operate said selector repeater over said trunk line for extending a toll call to a subscriber's line in the second exchange, and means including a toll board in the second exchange for operating said selector repeater to operate said incoming selector repeater over said trunk line for extending a toll call to a subscriber's line in the first exchange, and means in said incoming selector repeater for marking said outgoing repeater and said trunk line busy 70

in response to the operation of said incoming selector repeater over said trunk line.

3. In a telephone system, a first toll exchange, subscribers' lines terminating in said exchange, an outgoing repeater and an incoming selector repeater in the first exchange, a second toll exchange, subscribers' lines terminating in said second exchange, a two-way two-conductor trunk line interconnecting said exchanges, the two conductors of said trunk line normally connected to said incoming selector repeater by way of said outgoing repeater in the first exchange, a selector repeater terminating said trunk line in the second exchange, means including a toll operator's position in the first exchange for operating said outgoing repeater to disconnect said two conductors of said trunk line from said incoming selector repeater and to operate said selector repeater over said trunk line for extending a toll call to a subscriber's line in the second exchange, means including a toll board in the second exchange for operating said selector repeater to operate said incoming selector repeater over said trunk line for extending a toll call to a subscriber's line in the first exchange, and means in said selector repeater for marking said selector repeater and said trunk line busy in said toll board in response to the operation of said selector repeater over said trunk line.

4. In a telephone system, a first toll exchange, subscribers' lines terminating in said exchange, an outgoing repeater and an incoming selector repeater in the first exchange, a second toll exchange, subscribers' lines terminating in said second exchange, a two-way two-conductor trunk line interconnecting said exchanges, the two conductors of said trunk line normally connected to said incoming selector repeater by way of said outgoing repeater in the first exchange, a selector repeater terminating said trunk line in the second exchange, means including a toll operator's position in the first exchange for operating said outgoing repeater to disconnect said two conductors of said trunk line from said incoming selector repeater and to operate said selector repeater over said trunk line for extending a toll call to a subscriber's line in the second exchange, means including a toll board in the second exchange for operating said selector repeater to operate said incoming selector repeater over said trunk line for extending a toll call to a subscriber's line in the first exchange, and means in said selector repeater for reversing battery over said trunk line in a toll call to a subscriber's line in the second exchange, and means in said outgoing repeater responsive to said reversal of battery for transmitting high resistance supervision to said toll operator's position.

5. In a telephone system, a first toll exchange, subscribers' lines terminating in said exchange, an outgoing repeater and an incoming selector repeater in the first exchange, a second toll exchange, subscribers' lines terminating in said second exchange, a two-way two-conductor trunk line interconnecting said exchanges, the two conductors of said trunk line normally connected to said incoming selector repeater by way of said outgoing repeater in the first exchange, a selector repeater terminating said trunk line in the second exchange, means including a toll operator's position in the first exchange for operating said outgoing repeater to disconnect said two conductors of said trunk line from said incoming selector repeater and to operate said selector repeater over said trunk line for extending a toll 70

call to a subscriber's line in the second exchange, means including a toll board in the second exchange for operating said selector repeater to operate said incoming selector repeater over said 5 trunk line for extending a toll call to a subscriber's line in the first exchange, means in said incoming selector repeater for reversing battery over said trunk line in a toll call to a subscriber's line in the first exchange, and means in said selector repeater responsive to said reversal of battery for transmitting high resistance supervision to said toll board in the second exchange.

6. In a telephone system, a first toll exchange, an outgoing repeater and an incoming selector repeater in said exchange, a second toll exchange, subscribers' lines terminating in said second exchange, automatic switches in said second exchange having access to said subscribers' lines, a two-way two-conductor trunk line interconnecting said exchanges, the two conductors of said trunk line normally connected to said incoming selector repeater to extend incoming toll calls received over said trunk line from the second exchange, means including a toll operator's position in said first exchange for seizing and operating said outgoing repeater to disconnect said incoming selector repeater from said two line conductors of said trunk line and to operatively connect said trunk line to said outgoing repeater, 20 means at said operator's position for operating said outgoing repeater to control said automatic switches over said trunk to complete a connection to a subscriber's line in the second exchange, and automatic means for giving the toll operator switchhook supervision over the established connection.

7. In a supervisory bridge circuit comprising two normally open upper legs and two lower legs normally connected to one pole of battery, a relay 40 included in the first lower leg, means for completing the first upper leg from the other pole of battery to operate said relay, contacts on said relay for connecting said other pole of battery to complete the second upper leg, a supervisory controlling relay bridged between the junction of said upper and lower legs responsive to the operation of said first relay, a balanced circuit including said first and second upper legs for preventing the operation of said supervisory relay, said supervisory relay operated in series with said first relay in response to disconnecting the other pole of battery from said first upper leg and released in response to reconnecting said other pole of battery to said first upper leg.

55 8. In a supervisory circuit for use in telephone systems comprising a balancing supervisory bridge circuit including two normally open upper legs and two lower legs normally connected to one pole of battery, a relay included in the first lower leg, a resistance corresponding to the resistance of said relay included in the second lower leg, means for completing the upper leg from the other pole of battery to operate said relay, contacts controlled by said relay for completing the second upper leg by connecting the other pole of battery thereto, equal resistances included in both said upper legs, a second relay having one terminal of its winding connected to the midpoint of said second upper and said second lower legs, other contacts controlled by said first relay for connecting the other terminal of the second relay winding to the midpoint between the first lower leg and the first upper leg, said second relay energizing in response to the disconnection of said other pole of battery from said first upper

leg and deenergizing in response the reconnection of the other pole of battery to said first upper leg, and supervisory means controlled by said second relay.

9. In a supervisory bridge circuit comprising two upper and two lower legs, means for closing the first upper leg, a relay included in said first lower leg operated responsive to the closure of said first upper leg, a bridge between the junctions of the upper and lower legs completed responsive to the operation of said relay, a supervisory controlling relay included in said bridge, a balanced circuit comprising said first and second upper legs for preventing the operation of said supervisory relay, said supervisory relay being operated in series with said second upper leg and said first relay in response to the opening of said first upper leg and released in response to the reclosure of said first upper leg.

10. In a supervisory bridge circuit comprising two upper and two lower legs, means for closing the first upper leg, a relay included in said first lower leg responsive to the closure of said first upper leg, a bridge between the junctions of the upper and lower legs completed responsive to the operation of said relay, a supervisory controlling means included in said bridge thereafter operative only in response to the opening of said first leg, said relay being maintained operated responsive to the opening of said first upper leg, and said supervisory controlling means released responsive to the reclosure of said first upper leg.

11. In a supervisory circuit for use in telephone systems comprising a supervisory bridge circuit including two upper and two lower legs, means for closing the first upper leg, means in said first lower leg responsive to the closure of said first upper leg for closing the second upper leg and for completing a bridge between the junction of the upper and lower legs, and supervisory controlling means included in said bridge thereafter operated in response to opening said first leg and released in response to reclosing said first leg.

12. In a telephone system, a first relay, a circuit for said relay, means for closing said circuit to operate said relay, a second relay, a circuit for said second relay prepared responsive to the operation of said first relay, means only responsive to the opening of said first circuit for operating said second relay over said second circuit, said first relay being maintained operated in said second circuit, said second relay released in response to reclosing of said first circuit, and supervisory controlling circuits controlled by the operation of said second relay.

13. In a telephone system, a first exchange and a second exchange, a two-conductor trunk line connecting said exchanges, a toll board in the second exchange having access to said trunk line, means including automatic switches in the first exchange controlled by the toll operator over said trunk line for completing a connection to a called subscriber's line terminating in the first exchange, a pair of relays in one of said automatic switches, a circuit for operating the first of said relays completed by another of said automatic switches in response to the extension of the call to the called line, a circuit for the second of said relays prepared responsive to the operation of said first relay, means in said other automatic switch for intermittently opening and closing said first circuit in case the called subscriber's line is busy, said second circuit effective to operate said second relay only in response to the opening of said first circuit and effective to release said sec-

ond relay in response to each reclosure of said first circuit, said second relay thereby intermittently operated in response to the intermittent opening and closing of said first circuit, and means controlled by said second relay for intermittently reversing battery over said trunk line to give the toll operator at said toll board flash supervision.

14. In a telephone system, a first exchange and 10 a second exchange, a two conductor trunk line connecting said exchanges, a toll board in the second exchange having access to said trunk line, means including automatic switches in the first exchange controlled by the toll operator over 15 said trunk line for completing a connection to a called subscriber's line terminating in the first exchange, a pair of relays in one of said automatic switches, a circuit for operating the first of 20 said relays completed by another of said automatic switches in response to the extension of the call to the called line, a circuit for the second relay prepared responsive to the operation of said first relay, means in said other automatic switch for opening said first circuit in response to the 25 called subscriber removing his receiver from the switchhook and for reclosing said first circuit in response to the called subscriber replacing his receiver, said second circuit effective to operate said second relay only in response to the opening 30 of said first circuit and effective to release said second relay in response to the reclosure of said first circuit, and means controlled by said second relay for reversing battery over said trunk line to give the toll operator at said toll board switchhook supervision.

15. In a telephone system, a first exchange and a second exchange, a two-way two-conductor trunk line connecting said exchanges, a toll board in the second exchange having access to 40 said trunk line, means including automatic switches in the first exchange controlled by the toll operator over said trunk line for completing a connection to a called subscriber's line terminating in the first exchange, a pair of relays in 45 one of said automatic switches, a circuit for operating the first of said relays completed by another of said switches responsive to the extension of the call to the called line, a circuit for the second relay prepared responsive to the operation of said first relay, means in said other automatic switch for opening said first circuit in 50 response to the called subscriber answering, said second circuit effective to operate said second relay only in response to the opening of said first circuit, and means controlled by said second relay for reversing battery over said trunk line to give the toll operator at said toll board switchhook supervision.

16. In a telephone system, a first toll exchange, 60 subscribers' lines terminating in said exchange, automatic switches in said exchange, an incoming selector repeater in said exchange, a second toll exchange including a toll board, a trunk line interconnecting said exchanges and operatively connected to said incoming selector repeater and to said toll board, means including said toll board for seizing said trunk line and for operating said incoming selector repeater to control said auto-

matic switches to complete a toll connection to a called subscriber's line, a pair of relays in said incoming selector repeater, a circuit for operating the first of said relays completed by one of said automatic switches, a circuit for the second of 5 said relays prepared responsive to the operation of said first relay, means in one of said automatic switches for opening said first circuit, said second circuit effective to operate said second relay only in response to the opening of said first circuit, 10 and means controlled by said second relay for reversing battery over said trunk line for supervisory purposes.

17. In a telephone system, a first exchange, a second exchange, a two-conductor trunk line 15 connecting said exchanges, means including said trunk line for extending a call from said first exchange to a called subscriber's line terminating in the second exchange, means in said first exchange for momentarily connecting a battery potential to only one of said trunk conductors, said last means being automatically operative after the extension of the call to the called line, and ringing means in said second exchange responsive to said momentary battery connection to said 20 one trunk conductor for initiating the automatic ringing of the called subscriber.

18. In a telephone system, a first exchange, a second exchange, a two-conductor trunk line connecting said exchanges, means including a toll 30 operator's position in the first exchange for extending a call from said first exchange over said trunk line to a called subscriber's line terminating in the second exchange, means in said first exchange for connecting a battery potential to 35 only one of said trunk conductors, said last means being automatically and momentarily operated after the extension of the call to the called line and thereafter operated under manual control by the toll operator from said toll position, and ringing 40 means in said second exchange responsive to said automatic and momentary battery connection for initiating automatic ringing of the called line and thereafter responsive to said battery connection under control of the toll operator for 45 reringing the called subscriber.

19. In a telephone system, a first exchange, a second exchange, a two-conductor trunk line connecting said exchanges, means including a toll operator's position in the first exchange for 50 extending a call from said first exchange over said trunk line to a called subscriber's line terminating in the second exchange, means in said first exchange for connecting a battery potential to only one of said trunk conductors, said last 55 means being automatically operated after the extension of the call to the called line, a differential relay in said second exchange having two windings, the first of said windings being connected to said one trunk conductor and the second winding being connected to the other conductor of said trunk line, said relay only operated in response to said battery connection to said one 60 trunk conductor, and means controlled by the operation of said relay for ringing the called subscriber.

IRVIN GEITGEY.
